(57) **CLAIM**

The ornamental design for a vehicle, as shown and described.

DESCRIPTION

FIG. 1 is a front left side perspective view of the vehicle of the present invention;

FIG. 2 is a front right side perspective view thereof;

FIG. 3 is a rear right side perspective view thereof;

FIG. 4 is a right side rear perspective view thereof;

FIG. 5 is a rear left side perspective view thereof;

FIG. 6 is a left side view thereof;

FIG. 7 is a left side front perspective view thereof;

FIG. 8 is a top, rear, left side perspective view thereof with the top in an open position; and,

FIG. 9 is a top rear right side perspective view thereof.

The environment surrounding the vehicle in the figures does not form part of the claimed design.

The license plate letters and numbers do not form part of the claimed design.
